UNITED STATES PATENT OFFICE.

JACOB C. LUDEN, OF READING, PENNSYLVANIA.

DESIGN FOR A SUPPORT OR HOLDER FOR GARDEN-HOSE NOZZLES.

SPECIFICATION forming part of Design No. 32,691, dated May 22, 1900.

Application filed April 17, 1900. Serial No. 13,275. Term of patent 7 years.

To all whom it may concern:

Be it known that I, JACOB C. LUDEN, a citizen of the United States, residing at Reading, in the county of Berks and State of Pennsylvania, have invented and produced a new and original Design for a Support or Holder for Garden-Hose Nozzles; and I do hereby declare the following to be a full, clear, and exact description of the same, reference being had to the accompanying drawings, forming a part thereof.

This invention relates to a new and original design for a holder or support for a garden-hose nozzle.

15 In the drawings, Figure 1 is a front view, Fig. 2 an end view, and Fig. 3 a sectional view, taken on line $x-x$ of Fig. 1, of my holder or support.

The body or central portion A of my support is rectangular in cross-section and is 20 formed at its lower end with two right-angled pointed prongs a , forming a fork.

On the upper end of the body A is formed a head or holder B, approximately of crescent shape, forming slightly more than a semi-circle and formed with a circular enlargement b at its upper end. In cross-section this crescent-shaped head is approximately triangular, Fig. 3, and formed slightly at an angle to the body A, as shown in Fig. 2.

Having thus fully described my invention, what I claim is—

The design for a support or holder for a garden-hose nozzle, substantially as shown and described.

In testimony whereof I affix my signature in presence of two witnesses.

JACOB C. LUDEN.
